UNITED STATES PATENT OFFICE

SIMON CANTOR, OF BROOKLYN, NEW YORK, ASSIGNOR TO LA BELLE SPECIALTY CO., INC., OF NEW YORK, N. Y., A CORPORATION OF NEW YORK

DESIGN FOR A TORCHÈRE

Application filed May 16, 1930. Serial No. 35,668. Term of patent 3½ years.

To all whom it may concern:

Be it known that I, SIMON CANTOR, a citizen of the United States, residing at Brooklyn, in the county of Kings and State of New York, have invented a new, original, and ornamental Design for Torchères, of which the following is a specification, reference being had to the accompanying drawing, forming part thereof.

In the drawing—

I claim:

The ornamental design for a torchère, as shown.

SIMON CANTOR.
